UNITED STATES PATENT OFFICE.

MICHAEL CODY, OF CHICAGO, ILLINOIS.

TLTING EXTENSION FOR FIRE-ESCAPES.

SPECIFICATION forming part of Letters Patent No. 712,262, dated October 28, 1902.

Application filed May 31, 1902. Serial No. 109,702. (No model.)

To all whom it may concern:

Be it known that I, MICHAEL CODY, a citizen of the United States, residing at Chicago, in the county of Cook and State of Illinois, have 5 invented certain new and useful Improvements in Tilting Extensions for Fire-Escapes, of which the following is a specification.

My invention relates to certain improvements in fire-escapes, and has reference more 10 particularly to an improved tilting stairway or ladder designed to form a connection between the lower platform or balcony of an ordinary stationary fire-escape, which is usually located on the level with the second story 15 of a building, and the sidewalk or ground surface therebeneath.

Stationary fire-escapes of that class which are applied to the external walls of office-buildings, apartment-houses, and like structures 20 usually terminate at the second story of the building, for the reason that if extended entirely to the ground they would occupy space required for other purposes. In view of the fact that in many buildings the second 25 story is at such a height above the ground as would render it unsafe for persons in the exigencies of a fire to leap or jump therefrom to the ground various kinds of extensions in the nature of tilting stairways or ladders 30 have been proposed and employed in connection with and as an adjunct to the stationary structure of the escape, and my invention has to do with this last-mentioned class of devices, its principal object being to provide 35 an improved pivoted extension designed to afford a connection between the lowermost stationary platform or balcony and the ground when such a connection is required and to be tilted up out of the way of passers-by at all 40 other times.

More specifically, my invention relates to a novel and improved means for counterbalancing the pivoted section in such a way that the ladder may be raised and lowered with 45 the application of but a slight impulse in either direction, and, furthermore, may be lowered into operative position automatically, as it were, by which I mean that the mere act of the individual descending the same in 50 stepping from the stationary platform onto the topmost step of the ladder will depress

the latter and that so gradually as to avoid all danger of a fall on the part of the person descending the same.

To these and other minor ends my invention consists in an improved tilting ladder or stairway constituting the lowermost extension of a stationary fire-escape having the peculiar and novel features of construction and mode of operation, substantially as hereinafter described, and pointed out in the claims.

In the accompanying drawings, which illustrate the preferred embodiment of my invention, Figure 1 is a side elevational view of my 65 improved tilting stairway, the same being shown as connected to the lowermost platform of a stationary fire-escape, the full lines indicating its lowered or operative position and the dotted lines representing its elevated 70 or idle position. Fig. 2 is a top plan view of the same, and Fig. 3 is a transverse vertical sectional view on the line 3 3 of Fig. 1 looking in the direction of the arrow.

Referring to the drawings, 4 designates the 75 lower platform or balcony of a stationary fire-escape, such as is commonly applied to the external walls, as 5, of high buildings, and 6 indicates a vertical bracket which in coöperation with the wall of the building constitutes a support for said platform.

Pivoted on a rod 7, extending through the upper end of the bracket 6, just below the platform 4, is a short stairway or ladder 8, which is preferably provided with a hand-rail 85 9 and the upper end of which has a substantially horizontal extension 10, the outer end of which supports a stirrup 11 for a purpose hereinafter disclosed. Likewise pivoted upon the rod 7 and between the side rails of the 90 stairway is a box or casing 12, the bottom or lower wall of which is longitudinally slotted throughout the major portion thereof, as shown at 13 in Fig. 3, thereby providing a pair of inwardly-projecting flanges 14, that 95 constitute a track or way upon which may roll back and forth a counterweight in the nature of a heavy metal ball 15. It will be observed that the casing 12 is formed on the line of an arc of a circle, whereby the way or 100 track 14 is slightly curved in a vertical plane between the opposite ends of the casing. This

is for a purpose which will appear in connection with the description of the operation of the device. The casing 12 is hinged through the upper portion of its inner end relatively 5 to its supporting parts, while its outer portion seats in and is supported by the stirrup 11, carried by and between the rearward extensions 10 of the side members of the stairway.

- 10 The operation of the device is substantially as follows: The stairway is normally in the idle or elevated position, (indicated by dotted lines in Fig. 1,) in which position it will be observed that the counterweight (ball 15) assumes by gravity a position in the outer end of the casing 12, the weight of this ball and its distance from the pivot-rod being such as to slightly more than counterbalance the weight of the stairway. When a person 15 desires to descend from the platform 4 by means of the pivoted stairway, he simply steps from the platform onto the top step of the stairway, which step, it will be noticed, is so close to the fulcrum-rod that the effect of his weight 20 will be to very slowly overbalance and elevate the counterweight and its containing-casing, and thus cause the outer free end of the stairway to gradually descend to the ground, after which the person may easily 25 descend in safety. By the time the free end of the stairway is upon the ground the counterweight will have rolled from the outer to the inner end of its casing and will occupy the position shown in Fig. 1 in connection 30 with the full-line illustration of the mechanism, in which position the weight of the stairway will slightly overbalance that of the counterweight, thus causing the stairway to remain in its lowered position. A subsequent 35 slight lift of the free end of the stairway will start the ball again rolling toward the outer end of its casing, during which the ball will reach and pass the point of exact counterbalance between the weight and the 40 stairway and will then of itself serve to complete the elevation of the stairway and hold the same elevated.

- 45 It will be evident from the foregoing that the employment of a loose connection between the counterweight-casing and the stairway and the provision of means such as the extensions 10 and stirrup 11 are not absolutely essential to the carrying out of my invention, since the casing 12 might be made rigid with 50 the side members of the stairway; but I prefer the construction shown, for the reason that it is more convenient and economical to construct the stairway itself and the means for counterbalancing the same in separate parts.
- 55 The formation of the track or way 14 on which the counterweight rolls on a downwardly curved or dipped line, instead of on a straight line, secures a much more gradual travel of the counterweight from end to end 60 of its casing, and thus insures a more gradual rising-and-falling movement of the stair-

way. This latter is of large importance, especially in connection with the descending movement of the stairway, since a sudden and jerky drop of the stairway would inevitably be attended by the danger of pitching headlong the person attempting to descend the same. It is sometimes found desirable to effect a slight vertical adjustment of the outer portion of the track on which the ball 75 rolls in order to secure the most perfect balance of the parts and the most gradual and uniform movement of the stairway. To this end I may provide the stirrup 11 with a pair of adjusting-screws 16, whose manner of operation to effect this result is obvious.

Within the scope of the generically-novel mechanical features of the above-described device my invention is not limited to the specific details of construction or relative arrangement of the parts herein shown, since it is obvious that the same might be considerably modified by the substitution of mechanical equivalents without departing from the spirit of my invention.

I claim—

1. In a device of the character described, the combination with the platform of a stationary fire-escape, of a stairway pivoted at its upper end beneath the platform, a downwardly curved or dipped track or way rigidly connected with said stairway and extending rearwardly of its pivotal axis, and a counterweight adapted to move to and fro over said track or way in the operations of raising and 95 lowering the stairway, substantially as described.
2. In a device of the character described, the combination with the platform of a stationary fire-escape, of a stairway pivoted at its upper end beneath the platform, a casing connected with said stairway in rear of its pivotal axis, a downwardly curved or dipped track or way in said casing, and a ball-counterweight adapted to roll to and fro from end 100 to end of said casing in the operations of raising and lowering the stairway, substantially as described.
3. In a device of the character described, the combination with the lower balcony of a stationary fire-escape and a pivot-rod fixed therebeneath, of a stairway pivoted at its upper end on said rod and having its side frame members extended beyond the pivotal point, a casing pivoted at its inner end upon said 115 pivot-rod and at its outer part supported by and between said extensions of the stairway, a downwardly curved or dipped track in said casing, and a ball-counterweight adapted to roll to and fro from end to end of said casing 120 in the operations of raising and lowering the stairway, substantially as described.

4. In a device of the character described, the combination with the lower balcony of a stationary fire-escape and a pivot-rod fixed therebeneath, of a stairway pivoted at its upper end on said rod and having its side frame 130

members extended beyond the pivotal point, a stirrup hung transversely between and across the outer ends of said extensions, a casing pivoted at its inner end upon said pivot-rod and at its outer part seated in and supported by said stirrup, a downwardly curved or dipped track in said casing, and a ball-counterweight adapted to roll to and fro

from end to end of said casing in the operations of raising and lowering the stairway, to substantially as described.

MICHAEL CODY.
